HANDLE FOR A BROOM OR SIMILAR ARTICLE

Alfred L. Le Febvre, West Suffield, Conn., assignor to Stanley Home Products, Inc., Westfield, Mass., a corporation of Massachusetts

Application January 20, 1955, Serial No. 34,085

Term of patent 14 years

(Cl. D9—2)

Fig. 1.

Fig. 2.

Fig. 3.

Fig. 1 is a side elevational view of a handle for a broom or similar article showing my new design;

Fig. 2 is an enlarged, partial, longitudinal sectional view through the handle shown in Fig. 1; and

Fig. 3 is a cross sectional view on the line 3—3 of Fig. 1.

The handle has the same appearance on all sides thereof.
I claim:

The ornamental design for a handle for a broom or similar article, as shown and described.
